GAME BOARD

Sharon K. Philbin, 2642 NW. 12th, Oklahoma City, Okla.

Filed Dec. 23, 1963, Ser. No. 77,893

Term of patent 14 years

(Cl. D34—5)

FIG. 1

The essential features of my design are shown in full lines.

The shading of the various squares is for the purpose of designating contrast of color in a selected sequence but not indicating any particular color designations.

I claim:

The ornamental design for a game board, substantially as shown and described.
